(57) **CLAIM**

The ornamental design for a hair extension tool, as shown and described.

DESCRIPTION

FIG. 1 is a top front perspective view of the hair extension tool.

FIG. 2 is a top front perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof; and,

FIG. 9 is a top front perspective enlarged view of an end of the hair extension tool as identified in FIG. 2.

The broken lines in the drawings depicting the cone shaped element in FIG. 1 are for illustrative purposes only and form no part of the claimed design. The dash-dot-dash broken lines indicating the enlarged views in the drawings are for annotative purposes only and form no part of the claimed design.
